UNITED STATES PATENT OFFICE.

WILLIAM S. NOYES, OF CHICAGO, ILLINOIS, ASSIGNOR TO THE IMPERIAL BRASS MANUFACTURING COMPANY, OF CHICAGO, ILLINOIS, A CORPORATION OF ILLINOIS.

DESIGN FOR A BENCH-VALVE.

52,961.

Specification for Design.

Patented Feb. 4, 1919.

Application filed November 14, 1918. Serial No. 262,611. Term of patent 14 years.

To all whom it may concern:

Be it known that I, WILLIAM S. NOYES, a citizen of the United States, residing at Chicago, county of Cook, and State of Illinois, have invented a new, original, and ornamental Design for Bench-Valves, of which the following is a specification, reference being had to the accompanying drawing, forming a part thereof.

Figure 1 is a top plan view, and Fig. 2 is a side elevation of a bench valve, showing my new design.

I claim:

The ornamental design for a bench valve, as shown.

WILLIAM S. NOYES.
